UNITED STATES PATENT OFFICE.

ROBERT BONNER SHAW, OF WASHINGTON, NORTH CAROLINA, ASSIGNOR
OF ONE-HALF TO SAMUEL T. NICHOLSON, OF SAME PLACE.

DESIGN FOR A MUSIC-LEAF TURNER.

SPECIFICATION forming part of Design No. 23,103, dated March 6, 1894.

Application filed January 19, 1894. Serial No. 497,443. Term of patent 14 years.

To all whom it may concern:

Be it known that I, ROBERT BONNER SHAW, a citizen of the United States, residing at Washington, in the county of Beaufort and State of North Carolina, have invented a new and original Design for Music-Leaf Turners, of which the following is a specification.

My invention relates to a certain new and ornamental design in music-leaf turners, reference being had to the accompanying drawing, wherein I have illustrated the same in elevation.

The leading feature of my design is that when viewed in elevation it resembles the numeral 4, in that it comprises the outline of the numeral 4 and in addition has a circular head or disk-portion arranged at the apex or upper end of the 4.

1 designates the vertical stem of the resembled numeral, 2 the inclined portion, and 3 the transverse or horizontal portion. At the meeting ends of the vertical stem and inclined portion I locate the elliptical or disk-like end 4.

What I claim is—

The design for a music leaf turner herein shown and described.

In testimony that I claim the foregoing as my own I have hereto affixed my signature in the presence of two witnesses.

ROBERT BONNER SHAW.
